UNITED STATES PATENT OFFICE.

EUGENE SCHAUB, OF LOGAN, UTAH.

WATER STAGE AND DISCHARGE RECORDER.

1,336,090.

Specification of Letters Patent.

Patented Apr. 6, 1920.

Application filed July 26, 1916. Serial No. 111,373.

To all whom it may concern:

Be it known that I, EUGENE SCHAUB, a citizen of the United States, residing at Logan, county of Cache, and State of Utah, have invented a certain new and useful Water Stage and Discharge Recorder, of which the following is a specification.

This invention is a hydrographic instrument for ascertaining primarily the variation 10 in the height and volumes of natural bodies of water at various periods of time, and to produce a permanent record of such variations.

The objects of the invention are, first, to 15 produce a simple mechanism which is efficient in operation so as to produce automatically a continuous record of the variations in the height or discharge of a fluid during the hours of the day and night; second, to minimize the friction and wear on 20 the working parts by dispensing with gears and belts and making provision for the adjustment of parts to compensate for wear; to provide means adapted by adjustment 25 to obtain an indefinite number of scales; and to produce a record sheet which is free from atmospheric influences and is adapted for treatment in a manner to obtain an in- 30 effaceable or unalterable and permanent record, free from the uncertainties and defects inherent in the use of pencils and fluid-ink pens ordinarily employed in hydrographic and recording instruments generally.

35 A salient feature of the invention is a stylus-carrying member controllable by the rise and fall of a float and mounted for traveling and rotative movement relatively to a record sheet, the latter being under the 40 action of a clock train so as to be movable constantly and at definite speed, the plane of movement of the stylus-carrying element being at a right angle to the direction of movement of the record sheet.

45 A further feature of the invention consists of a special moisture-proof record sheet treated with hot wax, or equivalent material, containing a certain percentage of rosin, or its equivalent, combined with a transfer- 50 substance carrying member, such as a spool, and a stylus positioned to inscribe the surface of the prepared sheet in such manner that the transfer substance will be applied to the prepared record sheet and thus result in a 55 chart or diagram without the use of a pencil or

fluid-ink pen, which chart or diagram may, by subsequent treatment, be converted into a permanent record, such subsequent treatment consisting in heating the prepared sheet so as to incorporate the lines of the 60 transfer substance with the wax, whereby the lines of the chart or diagram are rendered ineffaceable and unalterable in the preservation of the record for an indefinite time.

65 The mechanism which it is preferred to use in connection with the waxed record sheet and the transfer substance comprises a control spool around which is wrapped a sheet of carbon or other transfer paper, a 70 feed spool on which the waxed paper is coiled and from which said waxed paper is conducted so as to contact with the transfer surface of the control spool, a take up spool for coiling the waxed paper after the latter 75 shall have been inscribed to produce the chart or diagram, and a clock train for driving the control spool at a certain predetermined speed.

80 The stylus-carrying element is embodied in a double cone the apices of which face in opposite directions, combined with suitable supporting rails, and suitable contact rails carried by the supporting rails, the surfaces 85 of said double cone being in direct frictional contact with convex surfaces of the contact rails, whereby the double cone is mounted for rotative movement upon and between the contact rails in a manner to minimize the friction and wear. The angularity of the 90 surfaces of the double cone may vary as required, and said rails are adapted to be shifted relatively to the double cone so that an indefinite number of scales may be obtained.

95 Said double cone carries a stylus positioned at the axis of rotation and free to move in the direction of said axis. The stylus forms a part of a spindle which slides in a bushing, the latter being in an axial bore provided in the hub of the double cone, and against this bushing is seated an incased spring, the tension of which is applied to impel the stylus into contact with the waxed record sheet with sufficient force 100 to produce the lines adapted to form the chart or diagram.

105 In the drawings.

Figure 1 is a side elevation of an instrument embodying this invention for record- 110

ing the stage and volume of water in natural bodies, irrigating ditches, etc.

Fig. 2 is a vertical cross section taken in the plane of the dotted line 2—2 of Fig. 1, 5 looking in the direction of the arrow.

Fig. 3 is a plan view of the instrument shown in Figs. 1 and 2.

Fig. 4 is a vertical section on an enlarged scale illustrating a part of the controlling 10 spool, the traveling double conical member which carries the stylus adapted for co-operation with said controlling spool, and the means for mounting said traveling member, whereby it is adapted for rotative and 15 traversing movement in a direction parallel to the axis of rotation of the controlling spool; and

Fig. 5 is a detail view of the recording stylus, illustrating one construction whereby 20 said stylus is adapted to be shifted out of contact with the record sheet.

A designates a controlling spool carried by a horizontal shaft *a* which is mounted in suitable bearings *a'* of a frame B, consisting of side plates fastened rigidly to a suitable base B'. The controlling spool is mounted loosely on shaft *a*, and this spool is driven at a constant predetermined speed by a time train of any suitable construction, the same being contained within a casting C suitably attached to the base B'. The time train is provided with an arbor *c* to which is fixed a gear pinion *c'*, the teeth of which are in mesh with the teeth of a 35 gear *c''* fixed to an end portion of the shaft *a*, whereby the time train is adapted to impart rotative movement to the controlling spool. This spool carries a transfer medium or substance, the same being herein 40 shown as a sheet D of carbon paper, but it is apparent that the spool may carry other forms of transfer material than the carbon sheet D.

The shaft *a* of the control spool extends 45 beyond the bearing *a'* provided for the end portion of the shaft opposite to the gear *c''*, whereby the shaft *a* is adapted to extend for a suitable distance beyond one of the frame plates. On this extended end of the shaft 50 is mounted a drum E, the latter being loose on the shaft so as to rotate in one direction independently of the shaft when winding up the gravity weight E', said gravity weight having a cord or cable *e* which is coiled on 55 the drum E. The weight drum E is provided with a ratchet hub *f*, the ratchet teeth of which are adapted for interlocking engagement with the teeth provided on a face of a ratchet F, the hub *f'* of said ratchet 60 being connected by a spline *f''* with the spool shaft *a*. The ratchet F is retained in interlocking engagement with the ratchet hub *f* of the weight drum by a coiled spring F' which is fitted loosely upon the protruding 65 end of the spool shaft *a*, whereby the

spring presses the ratchet F into engagement with the weight drum E so as to make said weight drum fast with the shaft *a* for imparting rotative movement to the spool A, the speed of said spool being under the 70 control of the time train. The spring F' is held from displacement on the shaft by a collar *f''*, or its equivalent.

In my instrument it is preferred to employ a moisture-proof record sheet G, the 75 same consisting of a sheet or web of paper coated or impregnated with paraffin, wax, or the like, the said sheet being prepared by running the fibrous material through a bath of melted wax, or equivalent material, containing about ten per cent. of rosin, after which the sheet is positioned for the excess material to drain off and is then dried in order to place it in condition suitable for use in the machine. It is evident that other 80 means of preparing the wax moisture-proof sheet may be employed without departing from the invention. A supply of the record sheet is coiled upon a feed spool G', the shaft *g* of which is mounted in open-ended 85 slots or other bearings provided in the frame plates B. The record sheet is conducted from the feed spool beneath the control spool A so as to have direct contact with the transfer sheet D carried by said control 90 spool. The record sheet is wound as required upon a take-up spool H, the latter being supported by shifting bearings so that the take-up spool will have frictional contact with the control spool sufficient to impart 95 rotative movement to the take-up spool, whereby traveling movement is imparted to the record sheet by the positively driven control spool, the latter acting to impart rotative movement to the take-up spool by reason of the frictional contact between the two spools A, H. The frictionally driven 100 take-up spool H is on a shaft which is fitted in open end bearings or slots *h* of swinging arms H' having pivotal connection at *h'* with the frame plates, said arms H', being inclined toward the control spool in order that the take-up spool may contact by the 105 weight thereof with said control spool.

I designates the traveling and rotatable 110 stylus-carrying member adapted for co-operation with the control spool, said member I being controlled by a counter-weighted float J. The member I is, in practice, a double cone, the surfaces *i*, *i'* of which face in 115 opposite directions, and the apices of said cones being in the plane of the axis of a hub *i''*. The periphery of the double cone member is provided with an annular groove *j* in which is fitted the cord or cable *j'* of the float, one end of said cable being attached to said float and the other end of the cable being fastened to a counter-weight J', whereby the rise and fall of the float imparts 120 rotative movement to the marking cone I. 125

As shown more particularly in Fig. 2, the two parts i i' of the double cone are provided with concentric sleeves fitted telescopically one within the other and constituting the hub i^2 . In one of the sleeves is an axial bore or passage k , adapted to accommodate a sleeve K which is slidable within the hub i^2 . The sleeve acts as a guide for a stylus spindle L , one end portion of which normally protrudes beyond the sleeve so that the stylus l is in frictional contact with the record sheet G . The sleeve K and the stylus spindle L are normally projected an operating distance beyond the hub of the double cone by a spring M incased within the hub and seated against one part of the cone, said spring acting against a follower m which is in contact with the inner end portion of the tube K and the stylus spindle L , see Fig. 4. The back thrust of the stylus on the spindle and the spring is taken up by an anti-friction ball N , the latter being rotatably fitted in a recess of the cone I . This thrust ball rides against the flange n of a rail N' , so that the action of the spring upon the cone I will not detract from the free rotation of the cone in its traversing movement with respect to the control spool A . It is preferred to divide the stylus spindle L so as to form a pivoted section L' , adapted to be held in fixed relation to the sleeve K by a pin o which fits in a bayonet groove o' provided in the sleeve K . It is apparent that the pivoted section L' of the stylus may be adjusted by withdrawing the stud o from the slot o' , thus allowing the pivoted section and the stylus to be shifted into and out-of-service position relatively to the record sheet and the control spool, thus making provision for the adjustment of the record sheet or the replacement of said sheet as desired, but when the instrument is in service the pivoted section carrying the stylus is locked to the sleeve K by adjusting the stud o in the bayonet slot of said sleeve.

The carrying member I is mounted for traversing movement by means which minimizes the frictional engagement of said marking member with its supporting means. To this end I provide supporting rails P , P' which are attached in a suitable way to downwardly converging standards p , the latter being suitably fastened to the base B' . The rails P , P' are recessed to accommodate contact rails Q , Q' , shown more clearly in Fig. 4. Each contact rail consists of a length or bar of metal circular in cross section, or having any other desired cross sectional form with a curved surface positioned for frictional contact with the conical surfaces i , i' of the member I . It will be noted by reference to Figs. 2 and 4 that the member I is positioned between the rails P , P' for the conical surfaces of said member to have frictional contact with the rails

Q , Q' , the convex surfaces of which afford very limited lines of contact between the member I and the rails Q , Q' .

The operation is apparent from the foregoing description, but may be summarized as follows:—

A sheet of carbon paper, preferably of good quality, is wound upon the control spool, the stylus being adjusted out of the way and the take-up spool being shifted away from the control spool. The prepared record sheet is wound upon the feed spool, and is conducted into contact with the transfer surface on the control spool and then wound upon the take-up spool, the latter being restored into contact with the control spool. The stylus having been readjusted into contact with the record sheet, the recorder is in condition for operation. Assuming the float does not rise or fall, it is apparent that the rotation of the control spool, the consequent feed of the record sheet and the operation of the stylus will result in a mark extending in a straight line along the record sheet. As the float rises or falls, the cable imparts rotative movement to the drum, and the frictional contact of said drum with the rails, causes a traversing movement to be given to the drum and the stylus, hence the conjoint action of the moving record sheet and the traveling stylus will produce on the record sheet a chart or diagram indicative of the condition of the water.

It is apparent that the diagram produced upon the record sheet is due to the pressure of the stylus against said sheet and the contact of the latter with the transfer surface. The record sheet is removed at the proper time and subjected to heat and pressure, so that the transfer material will become incorporated with the wax or paraffin on the record sheet, thus resulting in a permanent record.

It will be noted that the time train operates independently of the marking drum so that the time train continues in operation while adjusting the paper for time. The center of the conical marking drum does not change in elevation with respect to the central longitudinal axis of said drum, hence the pointer describes a straight line in its traversing movement from one side of the instrument to the other side. Further, by omitting the take-up spool and the feed spool, and increasing the diameter of the marking drum, it is possible to obtain a shorter time record. It is apparent that, by making the control drum longer, and using an additional cone and stylus, two curves may be produced simultaneously on the same sheet.

As shown, spreaders T are used between the carrying rails to maintain the latter in fixed relation. Said rails are parallel, as

shown, but they may be relatively inclined if desired, in which case the scale may vary from a natural to an exceedingly small scale, whereby a low condition may be graphically depicted, the same being very desirable in some cases.

All the working parts may obviously be incased to exclude moisture and dust. The stylus may be an alloy of nickel steel or any other suitable material. The instrument operates with very little friction, and with no apparent lost motion or cramping in any of its parts. It is sensitive to changes in the fluid level. By reason of the absence of gears and belts, the energy required to operate the marking spool is minimized, hence the translation in the rise and fall of the fluid is obtained in a most direct manner. The ratchet mechanism is a simple and effective contrivance for the time train weight. Apparently, the angularity of the conical drum can be varied as required, for the reason that slight changes in the angle may be demanded by practical service in order to secure good results. Said drum may be composed of metal, such as an alloy of steel, and any wear on the surface of said drum is compensated for by shifting the standard which forms a part of the drum guide.

In the drawings I have shown the double cone marking member I as having smooth surfaces *i i'*, but it is apparent that said surfaces *i i'* may be grooved or stepped in an obvious manner and for an apparent purpose.

Having thus fully described the invention, what I claim as new and desire to secure by Letters Patent is:

- 40 1. In a recorder of the class described, a bearing surface, a marking drum positioned for frictional contact with said bearing surface, and means for rotating said drum and to impart, by frictional contact with said bearing surface, a traversing movement to said drum relatively to the bearing surface, in combination with the record sheet, means for moving the same, and a stylus movable with said marking drum.
- 50 2. In a recorder of the class described, a bearing surface, a marking drum mounted in frictional contact with said bearing surface, and means for rotating said drum whereby the frictional contact of the rotatable drum with said bearing surface results in a traversing movement of the drum with respect to the bearing surface, in combination with a record sheet, means for feeding the same, a stylus movable with the marking drum, and means for impelling said stylus into forcible contact with said record sheet.
- 60 3. In a recorder of the class described, a bearing surface, a marking drum positioned for direct frictional contact with said bear-

ing surface, and means for rotating said drum whereby the frictional contact of the drum with the bearing surface results in a traversing movement of the drum with respect to said bearing surface, in combination 70 with a rotative member the axis of which is parallel to the line of traversing movement imparted to the marking drum, a transfer surface on said rotatable member, a time train for driving the rotatable member, a 75 record sheet in contact with the transfer surface of the rotatable member, and a stylus carried by the marking drum for contact under pressure with the record sheet.

4. In a recorder of the class described, the combination of a rotatable member, a transfer surface thereon, a time train for driving the rotatable member, a record sheet in direct contact with the transfer surface and adapted to be fed by the movement thereof, 80 a bearing surface parallel to the axis of rotation of the rotatable member, a marking drum mounted for direct frictional contact with said bearing surface, means for rotating the marking drum so that the frictional contact of said drum with the bearing surface will result in a traversing movement of the drum in a path parallel to the plane of the record sheet, and a yieldably mounted stylus movable with the marking drum and positioned for direct frictional contact with the record sheet.

5. In a recorder of the class described, a marking drum comprising tapering parts 100 positioned to face in opposite directions, and a plurality of rails constituting a bearing surface with which the tapering parts of the drum are in direct frictional contact, in combination with means for rotating said drum so as to impart thereto a traversing movement relatively to the rails, a record sheet, means for feeding said record sheet, a stylus mounted in said marking drum for movement in the plane of the axis of rotation thereof, and means for applying pressure to said stylus whereby it has forcible contact directly with said record sheet.

6. In a recorder of the class described, a plurality of rails constituting a bearing surface, and a double conical drum the members of which are in direct frictional contact with said rails, in combination with means for rotating said drum to impart thereto by reason of its frictional contact with the rails 115 a traversing movement with respect to the rails, a record sheet, means for feeding it, and a stylus mounted directly in the marking drum at the axis of rotation thereof, said stylus being movable into direct frictional 120 contact with said record sheet.

7. In a recorder of the class described, a plurality of rails constituting a bearing surface, a marking drum in frictional contact with said rails, and a spring actuated sty- 130

- lus mounted directly in the marking drum in the plane of the axis of rotation thereof, in combination with means for rotating said drum and by reason of its frictional contact with the rails imparting a traversing movement thereto, a rotatable member, a transfer surface thereon, a record sheet in contact with said transfer surface, and means for feeding the record sheet.
8. In a device of the class described, the combination with means for carrying a transfer surface, and means for presenting a fibrous sheet in contact therewith, of a track parallel to the surfaces of the transfer surface carrier and the fibrous sheet, a rotatable and traveling member supported by the track and movable along to the paper sheet and the transfer surface, a stylus slidably mounted on said rotatable and traveling member in the plane of the axis of rotation thereof, and means exerting pressure constantly on said stylus whereby it is impelled normally into contact with said fibrous sheet.
9. In a recorder of the class described, the combination of a rotatable member, a transfer surface thereon, a record sheet in direct frictional contact with said transfer surface, a bearing surface parallel to the axis of rotation of said rotatable member, a marking drum having direct frictional contact with said bearing surface, means for rotating said drum whereby the frictional contact of the drum with the bearing surface imparts a traversing motion to the drum with respect to the bearing surface and in a path substantially parallel to the surface of the record sheet, a stylus slidably mounted with respect to the rotatable and traveling drum, and means for applying pressure continuously to said stylus so as to retain it in forcible and direct contact with the record sheet, whereby said stylus coacts with the record sheet for effecting the transfer to the surface of said sheet of material from the transfer surface.
10. In a device of the class described, the combination with means for carrying a transfer surface, of separate means for feeding a fibrous sheet into contact with said transfer surface, a rotatable member mounted for traversing movement in a path substantially parallel to the surface of said fibrous sheet, a float and connections whereby rotative and traversing movement is imparted directly to said member, a stylus carried by said member and movable in the plane of the axis of rotation of said member, and pressure means coöperating with said stylus for exerting pressure constantly thereon.
- In testimony whereof, I have hereunto signed my name.

EUGENE SCHaub.
